UNITED STATES PATENT OFFICE

1,974,101

HOSPITAL BED

Adrian Comper, Pittsfield, Mass., assignor to
 Hospital Appliances, Inc., Pittsfield, Mass., a
 corporation of Massachusetts

Application February 1, 1933, Serial No. 654,720

17 Claims. (Cl. 5—90)

The invention relates to invalids' or hospital beds of the general type disclosed in U. S. patent to Adrian Comper, 1,884,577 of October 25, 1932, and the following U. S. patents to Joseph E. 5 Fazakerley: 1,293,721 of November 7, 1916; 1,257,072 of February 19, 1918; and 1,545,415 of July 7, 1925.

All of the above mentioned patents, disclose a bed having a mattress composed of head and 10 foot sections, and separable hip supporting sections; supporting means for said mattress sections including carriages for said hip sections and a supporting frame for said carriages; a bed pan elevator for lifting a bed pan into position 15 between said hip sections when the latter are separated, and operating means for said carriages and said elevator. The Comper Patent 1,884,577 also includes a jack operable in timed relation with the carriages and pan elevator, 20 for lifting one end of the head section of the mattress to elevate the patient's hips from said hip sections when the latter are to be moved. Beds embodying these features have been more or less successful but have been subject to certain 25 drawbacks which the present invention has aimed to overcome.

Every hospital insists upon equipment which may be easily kept immaculate and sanitary, and it has therefore been one of the foremost objects of the present invention to fulfill these requirements with a structure which could not only be easily kept in clean and sanitary condition under normal circumstances, but one which could be soiled only to the minimum and 30 could be expeditiously cleaned in case of any accidental or premature discharge of feces or urine. In carrying out that end, a further aim has been to provide a frame structure in which the mounting means for the carriages and elevator, and also the operating means therefor, 35 were located at the exterior of the supporting frame, thereby not only protecting these parts against reception of premature or accidental discharges, but allowing the interior of the frame 40 in the region of the bed pan, to be free of moving parts and projecting portions which would not only become soiled, but would be arduous to clean.

In most hospitals, the draw sheet is an article of standard equipment, and its longitudinal edges must be tucked under the edges of the mattress, and it has been another object of the invention to provide a structure absolutely free from any elements which could interfere with 55 such tucking in of the draw sheet. To this end,

another aim has been the provision of new and improved easily applied and released means for holding the hip sections of the mattress upon the carriages in such manner as to offer no obstruction to tucking of the draw sheet under 60 said hip sections.

From continual use, no matter how well the mattress be constructed, the inner ends of the hip sections thereof may often become more or less depressed to the discomfort of the patient, 65 and it has been another object of the invention to provide novel means whereby a nurse could easily elevate the inner ends of said hip sections to restore them to positions at which they would cause no discomfort. In providing for 70 this adjustment of the hip sections, a further object has been to provide a new and improved carriage structure including a novel track-supported chassis frame connected with the carriage operating means, and a hip section support of novel form pivoted to said chassis frame at its outer end and adjustably supported at its inner end upon said chassis frame.

In providing for easy operation of the carriages and mounting their operating means at 80 the exterior of the supporting frame, I have employed carriage-actuating worms driven by a single hand crank or the like which also effects operation of the aforementioned jack and pan elevator. These worms, in the structure disclosed, remain operatively connected at all 85 times with the carriages and the hand crank, and therefore rotate as long as the hand crank or the like is operated, either when opening the bed and elevating the bed pan, or when lowering 90 the pan and closing the bed. It has been a rather important object of my invention to provide worms of special construction which would not appreciably move the carriages until the jack acted to so lift the mattress head section 95 as to free the patient's hips from the carriage-supported hip sections of the mattress, said worms then acting to rapidly move the carriages throughout almost the entire length of their travel while the jack supported the mattress head section, and finally serving to slowly complete the remaining infinitesimal final carriage movement upon jack descent. By so doing, even 100 though the hip sections are moved somewhat while the patient's hips are resting upon them, the movement is so slight that no discomfort is caused and no appreciable resistance to operation of the bed. Moreover, the slow initial closing movement of the carriages after use of the bed 105 pan, allows the pan elevator to descend and 110

55 such tucking in of the draw sheet. To this end,

lower the pan sufficiently to permit easy after-cleaning of the patient, before appreciable closing of the mattress hip sections occurs.

In generally improving the bed, a number of 5 movable parts have been housed within a casing at the exterior of the supporting frame, said casing being secured to a vertical plate forming part of the frame. This same plate has been utilized to carry guide tracks for one end of the 10 pan elevator, and a further object of the invention has been to provide novel operating means for said elevator, connected with the track-guided end of the latter and housed to a large extent in the aforesaid casing.

15 In addition to the foregoing, it has been an object to provide a comparatively simple, inexpensive and light structure, yet one which would well resist all strains to which subjected.

With the foregoing in view, the invention 20 relates in the novel subject matter hereinafter described and claimed, description being accomplished by reference to the accompanying drawings.

Fig. 1 is a top plan view of the central portion 25 of a hospital bed constructed in accordance with the present invention.

Fig. 2 is a vertical sectional view cut transversely of the bed, on line 2—2 of Fig. 1.

Fig. 3 is a view somewhat similar to Fig. 2, 30 but showing the casing and a number of parts carried thereby, removed to disclose parts which would otherwise be hidden from view.

Fig. 4 is an inner side elevation of the casing and contained parts, omitted from Fig. 3.

35 Fig. 5 is a vertical sectional view in a plane extending longitudinally of the bed, on line 5—5 of Fig. 2.

Fig. 6 is a horizontal sectional view on line 6—6 of Fig. 5.

40 Fig. 7 is a vertical sectional view cut transversely of the bed on line 7—7 of Fig. 1.

Fig. 8 is a perspective view of the portion of the frame structure toward one end of the bed.

45 Fig. 9 is a similar view of the portion of the frame structure toward the other end of the bed.

Fig. 10 is a perspective view showing the chassis frame of one of the carriages for the hip sections of the mattress.

50 Fig. 11 is a perspective view showing the frame of one of the mattress section supports which are pivotally and adjustably mounted upon the chassis frames of the carriages, showing also the mattress section-holding means.

Fig. 12 is a perspective view showing the yoke 55 which is connected with the bed pan elevator and the operating cable for said elevator.

Fig. 13 is a detail sectional view on line 13—13 of Fig. 1.

Fig. 14 is a detail perspective view of one of the flange braces.

Fig. 15 is a detail perspective view showing one of the bearings of the worm-carrying shaft, which bearing acts also as a flange brace.

The head and foot sections of the mattress 65 are denoted at 20 and 21 respectively, and the two separable hip supporting sections are shown at 22. Carriages 23 are provided for the hip sections 22, a jack 24 is provided for the end of the head section 20 toward said hip sections 22, an elevator 25 is provided for a bed pan 26, and a frame structure 27 is employed to support 70 said carriages 23, jack 24, elevator 25, and the actuating means for these parts. The frame structure 27 is connected with spring-equipped 75 supporting linkage 28 and 29 for the head and

foot sections 20 and 21 of the mattress, said linkage being connected in any suitable way with the head and foot portions of the bed frame (not shown).

The frame 27 includes two side bars 30 and 30' disposed in spaced parallel relation and extending transversely of the bed, each of said side bars having both a horizontal longitudinally extending flange and a vertical longitudinally extending flange. The horizontal flanges are denoted at 31 and 31' respectively, and they are apertured for connection with the linkage 28 and 29. The vertical flanges are shown at 32 and 32' and these flanges are adapted to abut the adjacent ends of the mattress sections 20 and 21, respectively. The flanges 32 and 32' terminate in inwardly spaced relation with the ends of the side bars 30 and 30' so that they will not interfere with tucking of the conventional draw sheet under the edges of the mattress.

The central portions of the bars 30 and 30' are provided with parallel vertical plates 33 and 33', respectively, between which the bed pan elevator 25 is located, the vertical edges of the plate 33 being provided at the outer side of this

plate with vertical channel-shaped guide tracks 34 for said elevator 25, the latter being provided with rollers 35 engaged with said tracks. The parts 31, 32, 33 and 34 are preferably integral with each other, and said parts 31 and 33 are relatively braced by integral webs 36. Similarly, the parts 31', 32' and 33' are preferably integral with each other and relatively braced by integral bracing ribs 36'. Whereas the ribs 36 are short, the plate 33 being braced by the tracks 34, the ribs 36' preferably extend throughout the height of the plate 33'.

Between the plate 33 and the ends of the bar 30, this bar is provided with integral downwardly projecting lugs 37 and 38, portions of the lugs 37 being by preference integrally joined also to the upper portion of the plate 33 and the tracks 34. The bar 30' is provided with similar downwardly projecting lugs 37' and 38' respectively. Horizontal cross bars 39 and 40 extend between the lugs 37—37' and 38—38' respectively, and are secured thereto by cap screws or the like 41 and 41'. Additional horizontal cross bars 42 extend between the lower ends of the vertical plates 33 and 33' and are secured thereto by cap screws or the like 43, the two side members of the frame 27, being thus held in rigid relation. Bearings 44 are secured by two of the cap screws 41 and are provided with portions 45 which underlie and abut the flange 31 to effectively brace the latter near its ends, and right angular bracing members 45' are secured by the cap screws 41', said members 45' underlying and abutting the flange 31' to brace the latter. By the provision of the bracing means 45, 45', 36 and 36', the bars 30 and 30' are held against outward bending under the pull of the linkage 28—29, in a plane above the cross bars 39 and 40.

The outer sides of the bars 30 and 30' are provided with longitudinal channel-shaped tracks 46 and 46' respectively, in which rollers 47 of the carriages 23 are received, the exact manner of mounting said carriages being more clearly understandable after a specific explanation of the construction of one of said carriages. Each carriage includes a chassis frame 48 shown detached in Fig. 10, and a mattress section support having a supporting frame 49 illustrated detached in Fig. 11. Each chassis frame 48

- includes two inner side bars 50 and 50' disposed at the inner sides of the bars 30 and 30' respectively, and two outer side bars 51 and 51' disposed at the outer sides of said bars 30 and 30' respectively. The two bars 50 and 51 are integrally connected with each other by horizontal webs 52 which extend under the bar 30, the bars 50' and 51' are similarly connected by webs 52', and the inner ends of the bars 50 and 50' are integrally connected by a cross bar 53. The rollers 47 are mounted on the inner sides of the bars 51 and 51' and as the carriages 23 are moved, these rollers travel within the guide tracks 46 and 46'. 5
- 15 The mattress section-supporting frame 49 includes two parallel side bars 54 and 54', disposed at the inner sides of the chassis bars 50 and 50' respectively. The outer end portions of these bars 54 and 54' are pivoted at 55 and 55' to the bars 50 and 50' respectively and are integrally connected by an end bar 56. A cross bar 57 integrally connects the inner end portions of the bars 54 and 54' and carries a bolt 58 which is engaged with an adjusting nut 59, the latter being swiveled at 60 in the central portion of the chassis frame cross bar 53. Suitable linkage 61, having springs 61', is connected with the frames 49 and co-acts therewith in supporting the separable hip sections 22 of the mattress. 20
- 25 Whenever the inner ends of these hip sections become so depressed as to possibly be uncomfortable to the patient, they may be elevated by adjusting the nuts 59, such adjustments serving to tilt the two frames 49 with respect to the chassis frames 48. 30
- 35 The side bars 54 and 54' of the frame 49 are provided with upstanding longitudinal flanges 62 and 62' respectively, which engage the edges of the mattress sections 22, adjacent the head and foot sections 20—21, said flanges 62 and 62' terminating in inwardly spaced relation with the outer ends 56 of the two frames 49, so that they will not interfere with tucking of the draw sheet under the ends of said mattress sections 22. 40
- 45 The inner ends of the flanges 62 and 62' are connected by rods 63 to abut the inner ends of the hip sections 22, and U-shaped bails 64 are pivoted at 65 to the outer ends of said flanges 62 and 62', to embrace the outer ends of said sections 22. These bails not only hold the hip sections 22 against the rods 63, but they co-act with the flanges 62 and 62' in holding said hip sections against excessive dragging on the head and foot sections of the mattress during carriage shifting. The bails 64, being normally spaced above the end bars 56, do not interfere with inward tucking of the draw sheet. 50
- 55 A worm-carrying shaft 66 (Fig. 2) is disposed longitudinally of and at the outer side of the bar 30 above described, the ends of said shaft being mounted in the bearings 44. The intermediate portion of this shaft passes through the upper portion of a vertically elongated casing 67 which is received between the elevator tracks 34, said casing being secured by screws 68 to said tracks and by another screw 69 to the plate 33. At one or both points where shaft 66 passes through the vertical edge walls of the casing 67, a bearing 70 (Fig. 4) may be provided, and this bearing as well as all others used, are preferably of ball type. Preferably, the upper end of the casing 67 is provided with portions 71 which underlie and brace the flange 31 of the bar 30. 60
- 65 The ends of the shaft 66 are provided with worms 72 which are engaged with studs or the like 72' projecting outwardly from the carriage chassis bars 51 (Fig. 10). The inner end of each worm is slowly pitched as at 73, the outer end of the worm is similarly pitched as at 74, and between said portions 73—74, said worm is steeply pitched as shown at 75. With the two carriages 23 in their innermost positions and the hip sections 22 abutting each other, if the worms 72 be rotated to effect separation of said carriages and hip sections, the worm portions 73 move the carriages only an infinitesimal amount, while the jack 24 is operating to so raise the head section 20 as to lift the patient's hips from said sections 22, but as soon as the jack has performed its lifting function, the portions 75 of the worms 72, rapidly shift the carriages 23 outwardly throughout the greater part of their intended travel. Then, as the jack 24 starts to re-lower the head section 20 to position the patient on the bed pan which has in the meantime been raised by the elevator 25, the worm portions 74 slowly complete the infinitesimal final outward movement of the carriages 23. When the bed is to again be closed after use 100 of the bed pan, retrograde rotation of the worms 72 causes their portions 74 to only inappreciably move the carriages 23 inwardly while the jack 24 is again effecting lifting of the patient from the mattress sections 22. Such lifting having 105 been accomplished however, the portions 75 of the worms effect rapid return of the carriages 23 to almost the inward extreme of their travel. By this time, the jack 24 is again effecting lowering of the patient and the short final inward 110 movement of the carriages and the sections 22, is effected by the worm portions 73. 115
- It will be seen from the foregoing, that even though the mattress sections 22 are moved somewhat while in contact with the patient's hips, the slowly pitched worm portion 73 and 74 insure that said movement be so small that it shall interfere in no manner with the patient's comfort. 120
- For driving the worm shaft 66 and actuating elevator and jack operating parts, I provide an operating shaft 76 disposed below and parallel with said shaft 66, appropriate bearings 77, carried by the vertical edge walls of the casing 67 being provided for said shaft 76. The two 125 shafts 76 and 66 are operatively connected by a chain 78 and sprockets disposed within the casing 67. A suitable hand crank 79 or the like is provided for the shaft 76, and may well be connected projectibly and retractibly with said shaft 130 by means of a pin and slot connection 80.
- The shaft 76 extends across the interior of the casing 67 and is provided with a worm 81 meshing with a worm gear 82 on a shaft 83 which carries an operating cam 84 for the jack 135 24, said shaft 83 being mounted in bearings 83^a and 83^b (Fig. 5), carried by the plate 33 and the casing 67 respectively. When shaft 76 is rotated, it drives the cam 84 to operate the jack 24 and also drives the shaft 66 to cause the 140 worms 72 to actuate the carriages 23, jack movement and carriage movement being timed as above explained in connection with the different portions 73, 74 and 75 of the worms 72. 145
- Below and parallel with the shaft 83 is a short shaft 85 suitably mounted in the casing 67, said shaft 85 being provided with a cable drum 86 and with a pinion 87. This pinion is in co-operative relation with a gear segment 88 secured to the cam 84, said segment and pinion being out 150

of mesh as shown in Fig. 2, when the parts are in their normal positions. When said parts have been operated however, to separate the hip sections of the mattress to a sufficient extent, the 5 segment 88 meshes with and drives the pinion 87 thereby driving the cable drum 86. A cable 89 (Fig. 4) is wound on this drum, extends from the interior to the exterior of the casing 67, passes around guide sheaves 90, and is connected 10 at 91 (Fig. 5) with a yoke 92. This yoke extends partially around the casing 67 and is connected at 93 with the adjacent end of the elevator 25. It will thus be seen that when the drum 86 is driven as just explained, the cable 15 89 will be operated so as to lift the elevator 25, causing it to properly position the bed pan 26 between the hip sections 22, as the latter complete their outward movement and the jack 24 lowers the patient. After use of the bed pan, 20 the crank or the like 79 is turned in the reverse direction, causing lifting of the patient from the hip sections 22, lowering of the elevator 25, return movement of said hip sections 22 to normal position, and relowering of the patient onto said sections 22. The elevator 25 descends to quite an extent while the mattress sections 22 are being moved inwardly only to an infinitesimal extent, by the worm portions 74. This elevator descent also occurs at the time 25 30 when the patient is supported by means of the jack 24, so that ample room is given for after-cleaning the patient.

While the sequence of operations may be clear from the foregoing, they may be briefly set forth as follows:—Turning the crank or the like 35 in one direction causes the cam 84 to raise the jack 24 to lift the head section 20 of the mattress so as to lift the patient's hips from the hip-supporting sections 22. During such raising of the jack 24, the worm portions 73 move the carriages 23 only an infinitesimal amount, and while the cam 84 and jack 24 are supporting the patient slightly above the hip sections 22, the worm portions 40 45 75 come into play to rapidly shift said sections 22 outwardly. About this time, the jack 24 starts to lower and the worm portions 74 come into action. At about the same time, the gear segment 88 meshes with the pinion 87, thereby rotating the cable drum 86 and operating 50 55 the cable 89 to effect elevation of the bed pan 26 into its operative position, as the patient is finally lowered and the mattress sections 22 complete their final outward movement. To again restore the parts to normal after use of the bed pan, the crank or the like 79 is rotated in the opposite direction, causing reversal of the operations just described.

In addition to housing a number of the working parts within the casing 67, I prefer to 60 provide tubular housings 94 for the worms 72, said housings being supported at their inner ends by the casing 67 and at their outer ends by the bearings 44. The shank of the jack 24 extends into the casing 67 and may well be grooved 65 and engaged with anti-friction rollers 95. Bumpers 96 may well be provided on the ends of the bars 30 and 30' to engage the usual side rails of a bed frame when the mattress is supporting excessive weight. By removing the 70 bearings 44 and removing the screws 68—69, the casing 67 and the parts shown therein in Fig. 4, may be removed with the shaft 66 and worms 72, leaving the co-acting parts at the outer side of the plate 33, as seen in Fig. 3, it being of 75 course necessary to disconnect the yoke 92 from

the elevator 25 however, before casing 67 may be removed. It will thus be seen that access may readily be had to working parts whenever desired, and that the construction also facilitates manufacture and assembly. Preferably, the casing 67 is provided with a removable inspection plate 67' to permit observation of internal parts whenever advisable. 80

Particular attention is invited to the following:—The draw sheet may readily be tucked under the longitudinal edges of the mattress, without interference from any parts of the bed. All portions of the frame 27 in the region of the bed pan, are plane so that in case of an accident, the soiling parts will be at the minimum and 90 said parts may be quickly and easily cleaned. The carriage-mounting means and the carriage-operating means are disposed at the exterior of the frame 27 with no danger of being soiled or becoming entangled in bed clothing. The vertically adjustable portions of the carriages which support the hip sections 22, enable such adjustment of these hip sections as to restore the bed to a comfortable position, even if said hip sections become quite severely depressed. The means 100 for holding the hip sections 22 upon the carriages, not only allows quick and easy placing or removal of said hip sections, but holds them properly upon the carriages and does not interfere with tucking in of the draw sheet. The 105 worms for operating the carriages, not only insure easy operation, but the differently pitched portions of said worms insure that even though the hip sections 22 be moved while the patient is in contact with them, no discomfort shall result. 110 The pan elevating means is simple and advantageous in nature and is so located that there is little danger of it becoming soiled in case of an accident. 115

While the features of construction herein specifically explained, have proven advantageous from numerous standpoints, it is to be understood that within the scope of the invention as claimed, numerous variations may be made. If desired, the shaft 76 may project in the opposite direction from the casing 67, instead of projecting in the direction shown, positioning the handle 79 at the other side of the bed. The construction shown, is such as to readily permit this change to be made. 125

I claim:—

1. In a hospital bed of the type having a mattress composed of head and foot sections, and separable hip sections, and an elevator for positioning a bed pan between said hip sections, a frame having parallel horizontal bars to extend transversely of the bed and adapted for connection with head and foot sections of a mattress support, said bars being provided with upstanding flanges to abut the head and foot sections of the mattress, two parallel vertical plates between which said elevator is located, said plates projecting downwardly from said bars, the inner opposed sides of said bars, flanges and plates being plane to facilitate cleaning, supporting carriages for the aforesaid hip sections disposed between said bars, mounting means for said carriages disposed primarily at the outer sides of said bars, and guiding tracks for said elevator extending along the vertical edges of at least one 135 of said plates. 140

2. In a hospital bed of the type having a mattress composed of head and foot sections, and separable hip sections, and an elevator for positioning a bed pan between said sections; a frame 145

- having parallel side bars to extend transversely of the bed, said side bars each having an integral upstanding longitudinal flange, a central integral downwardly projecting plate in substantially the 5 same plane with said upstanding flange, and a longitudinal integral horizontal flange projecting outwardly from said upstanding flange and said plate; each of said side bars also having downwardly projecting integral lugs between its 10 ends and said plate, cross bars extending between the two side bars and secured to said lugs, additional cross bars extending between and secured to the lower ends of said plates, one of said plates having tracks for the aforesaid 15 elevator extending along its vertical edges, and carriages for the aforesaid hip sections disposed between said side bars, said side bars being provided along their outer sides with supporting tracks for said carriages.
- 20 3. A structure as specified in claim 2, together with bracing means for said horizontal flanges carried by the outer sides of said plates, and additional braces for said horizontal flanges secured to said lugs and spaced outwardly from 25 said carriage tracks.
4. A structure as specified in claim 2, together with bracing means for said horizontal flanges including a vertical casing for carriage and elevator operating parts, said casing being secured 30 to the outer side of said one plate and abutting the lower side of the flange which projects from this plate, said casing having vertical edge walls secured against said elevator tracks.
5. In a hospital bed of the type having a mattress composed of head and foot sections, and separable hip sections; a frame including parallel horizontal bars to extend transversely of the bed and adapted for connection with head and foot sections of a mattress support, said bars 40 having longitudinal tracks at their outer sides, and carriages between said bars for supporting the aforesaid hip sections of the mattress, said carriages each having a frame provided with portions underlying said bars, each carriage frame 45 being also provided with other portions extending upwardly from said bar-underlying portions and disposed at the outer sides of said bars, said upwardly extending frame portions having rollers engaged with said tracks.
- 50 6. In a hospital bed of the type having a mattress composed of head and foot sections, and separable hip sections; a frame including parallel horizontal bars to extend transversely of the bed and adapted for connection with head 55 and foot sections of a mattress support, said bars having longitudinal tracks at their outer sides, and carriages between said bars for supporting the aforesaid hip sections of the mattress, said carriages each having a frame provided with side bars at both the inner and outer 60 sides of the first named bars, cross bars connecting said inner side bars with each other, and horizontal webs underlying said first named bars and integrally joined to said inner and outer side bars, said outer side bars having rollers engaged with said tracks.
7. In a hospital bed of the type having a mattress composed of head and foot sections, and separable hip section; a carriage for each of 70 said hip sections comprising a shiftably mounted chassis frame, a mattress section support, means pivoting the outer end of said mattress section support to the outer end of said chassis frame, and vertically adjustable means supporting the 75 inner end of said mattress section support upon said chassis frame.
8. In a hospital bed of the type having a mattress composed of head and foot sections, and separable hip sections; a carriage for each of 80 said hip sections comprising a shiftably mounted chassis frame having a pair of parallel side bars and a cross bar connecting the inner ends of said side bars; a mattress section support having a pair of parallel side bars at the inner 85 sides of said chassis frame side bars, and a cross bar overlying said chassis frame cross bar and connecting the inner ends of said side bars of said mattress section support, means pivotally connecting the outer ends of the two pairs of side bars, and vertically adjustable means connecting said two cross bars.
9. In a hospital bed of the type having a mattress composed of head and foot sections, and separable hip sections; a shiftable carriage for 90 each of said hip sections having parallel upstanding flanges to abut the edges of the hip section adjacent the head and foot sections, said flanges terminating in inwardly spaced relation with the outer end of the carriage to allow 95 tucking of the usual draw sheet under the outer end of the hip section, a U-shaped bail adapted to embrace and abut the outer end of the hip section, the ends of said bail being connected with said flanges, and means on the carriage for 100 abutting the inner end of the hip section, said U-shaped bail holding said hip section against said abutting means and also co-acting with said flanges to hold said hip section against excessive dragging upon the head and foot sections 105 of the mattress during shifting of said carriage.
10. In a hospital bed of the type having a mattress composed of head and foot sections, and separable hip section; a shiftable carriage for 110 each of said hip sections having parallel upstanding flanges to abut the edges of the hip section adjacent the head and foot sections, said flanges terminating in inwardly spaced relation with the outer end of the carriage to allow 115 tucking of the usual draw sheet under the outer end of the hip section, a U-shaped bail adapted to embrace and abut the outer end of the hip section, the ends of said bail being connected with said flanges, and a rod to abut the inner 120 end of the hip section, the ends of said rod being secured to the inner ends of said flanges, said U-shaped bail serving to hold said hip section against said rod and also co-acting with said flanges to hold said hip section against excessive dragging upon the head and foot sections 125 of the carriage.
11. In a hospital bed of the type having a mattress composed of head and foot sections, and separable hip sections, shiftable carriages 130 for said hip sections, a frame supporting said carriages, and a jack for lifting the end of said head section adjacent said hip sections when the latter are to be moved; two carriage-actuating worms mounted on said frame and operatively 135 connected with said carriages respectively, and means for operating said jack and said worms, said worms having slowly pitched portions which only slightly move said carriages while said jack is lifting said head section, and also 140 having steeply pitched portions which then rapidly move said carriages.
12. In a hospital bed of the type having a mattress composed of head and foot sections, and separable hip sections, shiftable carriages 145

- for said hip sections, a frame supporting said carriages, and a jack for lifting the end of said head section adjacent said hip sections when the latter are to be moved; a shaft mounted on said frame and having two oppositely pitched carriage-actuating worms operatively connected with said carriages respectively, and means for driving said shaft and operating said jack, said worms having slowly pitched portions which only 5 slightly move said carriages while said jack is lifting said head section, and also having steeply pitched portions which then rapidly move said carriages. 13. In a hospital bed of the type having a mattress composed of head and foot sections, and separable hip sections, shiftable carriages for said hip sections, a frame supporting said carriages, and a jack for lifting the end of said head section adjacent said hip sections when the latter are to be moved; a shaft mounted on said frame and having two oppositely pitched carriage-actuating worms operatively connected with said carriages respectively, a rotatable cam for operating said jack, said cam being mounted 15 on an axis below and at right angles to said shaft, a worm gear co-axial with an operatively connected with said cam for rotating the latter, an operating shaft parallel with the afore- said shaft and having a worm meshing with said 20 worm gear, and driving connections from said operating shaft to the worm-carrying shaft. 14. A structure as specified in claim 13; said carriage-actuating worms having slowly pitched portions which only slightly move said carriage 25 while said cam is raising said jack, and also having steeply pitched portions which then rapidly move said carriages. 15. In a hospital bed, of the type having a mattress composed of head and foot sections, and separable hip sections, shiftable carriages for said hip sections, a supporting frame for said carriages, and an elevator mounted on said frame for positioning a bed pan between said hip sections; means for operating said carriages including a rotatable member mounted on 30 said frame; a gear segment carried by said rotatable member, a cable drum mounted on said frame and having a driving pinion in co-operative relation with but normally out of mesh with said gear segment, a cable having a portion wound on said drum, said cable being connected with said elevator, and guide sheaves for said cable mounted on said frame near the ends of the elevator path, said gear segment being adapted to mesh with said pinion to effect ascent of said elevator when said carriages and 35 hip sections have been sufficiently separated. 16. In a hospital bed of the type having a mattress composed of head and foot sections, and shiftable hip sections, carriages for said hip sections, a supporting frame for said carriages, a jack for lifting the end of said head section adjacent said hip sections when the latter are to be moved, and an elevator for positioning a bed pan between said hip sections; an actuating cam for said jack rotatably mounted on said frame below said carriages, an operating shaft mounted on said frame and operatively connected with said cam for rotating the latter, actuating means for said carriages operatively connected with and actuated by 40 said operating shaft, actuating means for said elevator including a cable and a drum for said cable, said drum having a driving pinion, and a gear segment rotatable bodily with said cam for engagement with said pinion to effect operation of said jack. 17. In a hospital bed having separable mattress sections, an elevator for positioning a bed pan between said sections, and carriages for said mattress sections; a supporting frame for 45 said carriages having a vertical casing containing carriage operating parts, guide tracks for said elevator extending along the vertical edge walls of said casing, a yoke extending partially around said casing and connected with said elevator, a cable connected with said yoke and extending into said casing, guide means for said cable, and operating means for said cable housed within said casing. 50 ADRIAN COMPER. 120
